FUSE PLUG

Leroy A. Kauffman, Washington, D. C., assignor
to Indicating Fuse Manufacturing Corporation,
Washington, D. C., a corporation of Delaware

Application April 24, 1935, Serial No. 18,038
Renewed February 6, 1937

5 Claims. (Cl. 200—121)

The present invention relates to fuse plugs adapted to be placed within the standard cut-out base of the conventional electric wiring systems whereby, should an overload or short circuit occur in the wiring system, the fusible element will become blown or ruptured in order to break the electrical circuit.

The invention has amongst its primary objects to provide a one-piece casing for fuse plugs of this character which can be molded from glass, porcelain, bakelite, or similar insulating materials and when so formed, the fusible element and contacts may be readily and easily applied thereto and connected for greatly reducing the 15 manufacturing cost thereof and thereby rendering the same commercially desirable.

Another equally important object of the invention is to provide a one-piece molded casing for indicating fuse plugs having several compartments formed therein and which compartments are so separated as to permit an indicator to be placed within one compartment and a fusible element to be placed in another compartment of the casing whereby, the successful operation of 25 the indicator will not in any manner be interfered with during the blowing of the fusible element.

Still a further object of the present invention is to provide a lamp indicator fuse comprising a 30 casing formed in one piece of molded insulating material to which the usual electrical contacts may be attached having a vertical compartment for receiving a lamp indicator and another compartment spaced and separated from said vertical 35 compartment for housing the fusible element.

Other objects of the invention will be in part obvious and in part pointed out hereinafter.

In order that the invention and its mode of operation may be readily understood by persons 40 skilled in the art, I have in the accompanying illustrative drawing and in the detailed following description based thereon, set out one possible embodiment of the same.

In this drawing:

45 Figure 1 is a vertical section through the fuse plug embodying the present invention;

Figure 2 is a vertical section through the molded one-piece casing of the fuse plug;

Figure 3 is a horizontal section taken on the 50 line 3—3 of Figure 2 in the direction of the arrow points, and

Figure 4 is another horizontal section taken on the line 4—4 of Figure 2 in the direction of the arrow points.

55 Referring now more particularly to the accom-

panying drawing, wherein like and corresponding parts are designated by similar reference characters throughout the several views, I have herein shown a plug fuse comprising a casing molded in a single piece of insulating material. This casing comprises a body portion 1 having a central bore extending vertically therethrough and the upper end of this bore 2 being of greater diameter than the lower end 3 thereof. An annular cavity 4 is formed within the body portion of the casing and has an opening 5 which communicates with the section 3 of the vertical bore formed within the casing. Another opening 6 is formed within the body portion of the casing having one end connecting to the section 2 of the vertical bore and its outer end terminating with the outer face of the casing. An annular depression 7 may be formed in the upper end of the fuse casing in order to reduce the amount of material needed in molding the casing and further to provide a suitable space for the markings such as the name of the manufacturers, amperes and volts which are to be carried by the particular fuse of which this casing forms a part. The upper end of the fuse casing is provided with the usual serrations 8 and the outer sides of the casing have formed therewith threads 9.

From the construction herein set forth, it is quite obvious that a casing made in accordance with the present invention can be molded from porcelain, glass, bakelite, or similar insulating material and after it has been so molded, a central contact consisting of a brass rivet 10 may be inserted within the section 3 of the vertical bore formed within the casing and a conventional threaded contact shell 11 may surround a portion of the casing and by engaging screw threads 9 formed with the casing, be retained thereon. A fusible element comprising a zinc strip 12 is positioned within the annular chamber or groove 4 of the casing which latter forms the fuse compartment of the fuse. One end 13 of this fuse strip is positioned between the shell 11 and the threads 9 and may be secured to the shell by solder or other suitable fastening means. The opposite end of this fuse strip extends through the opening 5 and has a wedging engagement with the upper end of the rivet 10. A glow lamp indicator 14 may be inserted within the upper section 2 of the central bore formed within the body portion of the casing having one terminal or lead-in wire connected to the rivet 10, whereas, the opposite lead-in wire of this glow lamp extends along the side of the lamp adjacent the inner end of the 55

opening 6 formed within the body of the casing. When the rivet 8 is forced within the bore 3 of the casing, the upper end thereof will have a wedging engagement between one terminal of the 5 lamp, one end of the fuse strip 12 and the casing for establishing a suitable contact between the lead-in wire, fuse strip and rivet and thereby fastening these respective parts together. A resistor 15 completely fills this opening 6 whereby it 10 will form a connection between that terminal of the lamp 14 which is positioned adjacent the opening 6 and the upper end of the contact shell 11.

A fuse made in accordance with the above construction may be inserted within the sockets of 15 the usual cut-out bases of electrical wiring systems and when so applied, the current will flow in the usual manner through the fuse link 12 but should an overload or short circuit occur in the wiring system, which would cause this fuse link to 20 become blown or ruptured, a circuit would be established in which the lamp 14 is included, thereby causing the same to glow and give off a visible signal.

Should it become necessary to further seal the 25 lamp compartment in order to prevent dust or lint entering the same and accumulating about the fuse link arranged therein, a cylindrical tube 16 of suitable insulating material may be placed within the compartment in the manner as is 30 illustrated in Figure 1 of the drawing.

Manifestly, the construction herein shown is capable of considerable modification and such modifications as come within the scope of my 35 claims, I consider within the spirit of my invention.

I claim:—

1. A fuse plug comprising a casing molded in a single piece of insulating material having an axially arranged lamp compartment and a bore 40 extending axially of the casing from the inner end of the lamp compartment, the outer end of said lamp compartment being opened, a central contact fitted into said bore through the outer end thereof, a threaded contact shell about said casing and together with the casing defining an annular chamber, a fusible element in said chamber connecting said contacts, a glow lamp adapted to be inserted through the outer opened end of said lamp compartment and rest within said lamp compartment, one terminal of said lamp being 45 connected to the inner end of said central contact, said casing having a passage formed therein with its inner end communicating with said lamp compartment and its outer end covered by said shell, a resistor arranged within said recess and said resistor electrically connecting said threaded contact shell and the other terminal of said lamp.

2. A fuse plug comprising a casing having a lamp compartment and a fuse compartment spaced therefrom, a central contact rivet mounted 50 within said casing and having one end extending within said fuse compartment, a threaded contact shell, a fusible element arranged within said fuse compartment, and being connected to said contact rivet and shell, a glow lamp arranged within said lamp compartment, one terminal of said lamp being connected to said contact rivet, said

casing having a recess formed therein communicating with said lamp compartment, a plastic resistance composition completely filling said recess, the other terminal of said lamp being connected to one end of said resistance composition and the 5 opposite end thereof contacting said threaded contact shell.

3. As an article of manufacture, a casing for fuse plugs consisting of a unitary body structure molded in a single piece of insulating material 10 and having a centrally located bore extending through the longitudinal axis of said body, said body having an external annular recess formed therein about a portion of the bore and at one point being extended inwardly of the body and communicating with said centrally located bore, screw threads formed with the outer periphery of 15 said body and said body having an opening formed therein in spaced relation to the recess and extending at right angles to and communicating with said centrally located bore. 20

4. As an article of manufacture, a fuse plug casing consisting of a body formed in a single piece of molded insulating material having a central opening extending therethrough, one end of 25 said opening being of greater diameter than that of the remaining portion or end thereof for establishing a lamp compartment, said body having an annular recess formed in the outer periphery thereof communicating with said central opening, said body having a resistor retaining opening formed therein and extending at right angles to said central opening, one end of said resistor opening having communication with said central opening and its opposite or outer end communicating 30 with the outer side of said body. 35

5. An indicator plug fuse comprising a casing molded in a single piece of insulating material having a central bore extending entirely through the longitudinal axis thereof, one end of said bore being of greater diameter than that of the opposite end thereof in order to provide a lamp compartment, a rivet mounted within said bore and providing a central contact for the fuse, said casing having an annular recess formed therein communicating with said centrally located bore, a threaded contact shell connected to said casing and closing the outer opened end of said annular recess, a fuse link positioned within said annular recess and electrically connecting said rivet with 40 said threaded shell, a glow lamp positioned within said lamp compartment of said centrally located bore, said casing having a resistance element retaining opening formed therein extending at right angles to said central bore and communicating with the lamp compartment thereof, one terminal of said glow lamp being electrically connected to said rivet, the other terminal of said glow lamp extending within said resistance element retaining opening of the casing, a plastic 45 resistance composition filling said resistance element retaining opening of the casing and said plastic resistance composition electrically connecting the terminal of the lamp extending within the resistance element retaining opening with 50 said threaded contact shell. 55
